U.S. Cl. D14—3

FIG. 1

FIG. 2

FIG. 3

FIG. 4

FIG.5

FIG.6

FIG. 1 is a perspective view from the front right corner of an automobile showing the doors closed and the headlights open embodying my novel design;

FIG. 2 is a front elevational view of the automobile of FIG. 1 with the doors and headlights closed;

FIG. 3 is a right side elevational view of the automobile of FIG. 1, the left side being symmetrically identical;

FIG. 4 is a perspective view taken from the right rear of the automobile of FIG. 1;

FIG. 5 is a rear elevational view of the automobile of FIG. 1;

FIG. 6 is a perspective view taken from in front of the automobile of FIG. 1 showing the same with the headlights closed and the doors open;

FIG. 7 is a partial cross-sectional view taken within the area of line VII—VII of FIG. 3; and

FIG. 8 is a top plan view of the automobile of FIG. 1.

We claim:

The ornamental design for an automobile, as shown and described.
